US0D1101538S

(12) **United States Design Patent** (10) **Patent No.:** **US D1,101,538 S**
(45) **Date of Patent:** **** Nov. 11, 2025**

(54) **DEADBOLT**

(71) Applicant: **ASSA ABLOY Americas Residential Inc.**, New Haven, CT (US)

(72) Inventor: **Elliott Schneider**, Foothill Ranch, CA (US)

(73) Assignee: **ASSA ABLOY Americas Residential Inc.**, New Haven, CT (US)

(**) Term: **15 Years**

(21) Appl. No.: **29/913,541**

(22) Filed: **Oct. 4, 2023**

Related U.S. Application Data

(62) Division of application No. 29/818,419, filed on Dec. 8, 2021, now Pat. No. Des. 1,028,679.

(74) *Attorney, Agent, or Firm* — Merchant & Gould P.C.

(57) **CLAIM**

The ornamental design for a deadbolt as shown and described.

DESCRIPTION

FIG. 1 is a front perspective view of a deadbolt showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines showing the lock element form no part of the claimed design.

1 Claim, 6 Drawing Sheets
